COATING APPARATUS

Harold A. Roselund, Toledo, Ohio, assignor to The
De Vilbiss Company, Toledo, Ohio, a corpora-
tion of Ohio

Application August 3, 1939, Serial No. 288,091

6 Claims. (Cl. 91—45)

This invention relates to spray coating apparatus and is more particularly related to apparatus for coating the interior surfaces of articles having polygonal cavities.

It has heretofore been difficult to put an even coating on the interior of receptacles such as muffin tins, bread pans or the like by means of spray coating equipment, since the preponderance of material was deposited in the bottom of the receptacle, and if sufficient coating material were applied to the sides, the coating on the bottom was found to be too thick while if the proper depth of coating was maintained on the bottom, the sides were found to be insufficiently coated.

The primary object of the present invention is the provision of means to coat the interior of a polygonal cavity evenly and to accomplish the coating by a simple and effective mechanism for moving a spray gun in a predetermined path so that its discharge effectively and evenly coats the interior of a shallow body.

Another object of the invention is the provision of improved means for exhausting a spraying chamber in which semi-solids are sprayed to permit settling and recovery of the sprayed particles.

Other objects and advantages of the invention will become apparent as the description proceeds, reference being had to the accompanying drawings, in which—

Figure 1 is a perspective view of a machine embodying the present invention;

Fig. 2 is a fragmentary sectional view of a receptacle to be coated;

Fig. 3 is a fragmentary section on line 3—3 of Fig. 1;

Fig. 4 is a vertical section on line 4—4 of Fig. 1;

Fig. 5 is a perspective view of the gun mounting apparatus in spraying position and shown in connection with a receptacle being coated;

Fig. 6 is a vertical elevational view of a spray gun mount;

Fig. 7 is a side elevation, with parts in section, the section being taken on line 7—7 of Fig. 8, and

Fig. 8 is a sectional view on line 8—8 of Fig. 7.

Referring to the drawings, the preferred embodiment of the machine includes a frame part 10 which carries a conveyor belt 11 mounted on suitable sheaves 12 at each end of the machine and driven through a motor 13 housed within the machine, by means of a belt or other driving connection 14. A gun housing 16 is provided and receives a material carrying line 17 and an air line 18 which are connected to the spray guns within the housing in a manner more fully de-

scribed hereinafter. An exhaust hood 20 is formed in the top of the machine and is subsequent, in the line of travel, to the gun housing 16 so that pans carried by the conveyor belt are presented first to the gun housing and subsequently pass under the exhaust hood 20. The movement of the pans, therefore, is in the direction of the arrows in Fig. 1.

In Fig. 5 the interior of the gun housing 16, the gun mountings and the gun driving mechanism are shown. In this figure the movement of the conveyor belt and pans is in the direction of the arrows, that is, from left to right in the figure. As shown, a plurality of spray guns 21 are mounted at spaced intervals across the machine and each of them is connected with the material conduit 17 through flexible connections 22 and with the air line 18 through flexible connections 24. The relationship between the spray guns 21 and the flexible material carrying conduits 22 and air line 24 is shown in Fig. 7. These connections are conventional, as is the spray gun, and form no part of the present invention.

The present invention is particularly directed to the means to mount the spray guns 21 in such a manner that their discharge ends are caused to move in a predetermined and adjustable orbital path so that material sprayed therefrom coats evenly the interior surface of a cylindrical or other polygonal receptacle such as the muffin tin shown in Fig. 5. A universal mounting for each gun is provided for this purpose and, as shown in Figs. 6, 7 and 8, each gun is mounted in a U-shaped yoke 30 by means of pintles 32 and is directly carried by a bracket 34. The yoke 30 is carried by a sub-frame member 36 which extends transversely of the machine and is mounted therein on a stub shaft 38 so that the yoke may rotate about the axis of the shaft, the latter being journaled in suitable bushings in the sub-frame member. It will thus be seen that the spray gun body is free to rotate about the axis of pintles 32 and also about the axis of stub shaft 38 so that an orbital movement may be imparted to the gun body causing it to discharge not only forwardly and rearwardly, but also to each side.

The bracket 34 to which the gun body is directly attached is connected by means of upwardly extending rods 40 to a drive plate 42 which latter has a universal driving connection with a connecting rod 44 through a spherically headed member 46 which cooperates with a cup element 48 carried by the driving plate 42. Motion imparted to the connecting rod 44 will be trans-

mitted to plate 42 and thence to the gun through the driving connection.

Referring to Fig. 3, it will be seen that the connecting rod 44 is driven from an electric motor 48 through the medium of reduction gearing driving a shaft 50. The shaft 50 carries a crank arm 52 to which the connecting rod is connected. Provision may be made for the adjustment of the effective length of crank arm 42 to alter the crank throw if it is found desirable. This provision may simply take the form of a slotted crank arm and a pin connection for the connecting rod 44. The connections for the connecting rod 44 are preferably duplicated at each end so as to provide uniformity of movement. At the end opposite the motor a bearing shaft 54 is mounted in a suitable bracket 56 carried by the frame of the machine and is connected to a pulley 58 similar in size to a companion drive pulley 60 driven by drive shaft 50. The two pulleys are connected by a belt 62.

It will be seen from the above described driving connections that with the parts shown in the position in Fig. 5, the discharge is toward the rear side of the approaching muffin tins. Movement of the crank arm 52 will pull the connecting rod 44 around to a forward position and in so doing will move the gun body in a circular path, tilting it both about the axis of shaft 38 and at the same time about the mounting pintles 32. When the connecting rod has reached its diametrically opposite position, the direction of discharge will be toward the rear of the muffin tins so that the guns will effectively coat the surface opposite to that being coated in the position shown in Fig. 5. It will be seen that during the time the guns have moved from one position to the other, one lateral wall will have received its coating. Return of the guns to the position shown will coat the opposite lateral wall. The length of the orbital path of the spray guns may be adjusted for small or large receptacles by adjusting the throw of the crank which drives connecting rod 44. For small receptacles a short throw will suffice, while larger receptacles require a longer crank throw to produce greater movement of the spray guns.

An exhaust chamber, constructed substantially as shown in Fig. 4 is provided adjacent the chamber in which the spray guns are mounted. The exhaust hood 20 does not communicate directly with the spray chamber, however, but is baffled therefrom by a lateral wall 64 which has depending side flanges 66 extending downwardly, preferably below the plane of the conveyor belt 11. At each side of the machine a housing 68 is formed which communicates at its upper end with the exhaust hood 20 and which has a volume greatly in excess of the volume between baffle 64 and the surface of the conveyor belt so that solid particles carried by the air stream into the housing will be deposited within the chambers 68 and the air alone exhausted through hood 20.

Any suitable means may be used to regulate the discharge of the spray guns 21 and any desired type of gun construction may be employed. While the invention has been described in connection with a particular form and disposition of the parts, various changes will suggest themselves to those skilled in the art. Such changes may be made without departing from the invention as defined in the appended claims.

What I claim as new and desire to secure by United States Letters Patent is:

1. A machine of the class described, having means to convey articles to be coated and spray

discharge means overlying the path of said articles, mounting means for said spray discharge means including a pivotally mounted yoke, a bracket carrying the spray discharge means and mounted on said yoke for pivotal movement perpendicular to the pivotal movement of said yoke, driving means, and means to drive said bracket from said driving means including a crank, a connecting rod, and a universal connection interposed between said connecting rod and the bracket, whereby said spray discharge means is driven in a path such that the bracket pivots with respect to said yoke and said yoke simultaneously pivots about its mounting to produce an even coating on all interior surfaces of an article passing under said spray discharge means.

2. In a machine of the class described, means to support articles to be coated, spray discharge means overlying articles supported by said last means, mounting means for said spray discharge means including a pivotally mounted yoke, a bracket carrying the spray discharge means and pivotally mounted on said yoke the pivotal axes of said yoke and said bracket being co-planar and perpendicular, driving means, and means to drive said bracket from said driving means including a crank, a connecting rod, and a universal connection interposed between said connecting rod and the bracket, whereby said spray discharge means is driven in a path such that the bracket pivots with respect to said yoke and said yoke simultaneously pivots about its mounting to produce an even coating on all interior surfaces of an article disposed under said spray discharge means.

3. In a machine of the class described, means to support articles to be coated, spray discharge means overlying articles supported by said last means, a mounting bracket engaging the spray discharge means intermediate the ends thereof, a yoke pivotally supporting the ends of said bracket, and means pivotally mounting a portion of said yoke for movement about an axis perpendicular to the axis of movement between said bracket and said yoke, means to drive said bracket including a crank, a connecting rod, and a universal connection interposed between said connecting rod and said bracket, whereby said spray discharge means is driven in a path such that the bracket pivots with respect to said yoke and said yoke simultaneously pivots about its mounting to produce an even coating on all interior surfaces on an article disposed under said spray discharge means, and means to adjust the throw of said connecting rod to vary the radius of the path of the discharge from said spray discharge means.

4. In a machine of the class described, having means to convey articles to be coated and having spray discharge means directed toward the path of said articles, mounting means for said spray discharge means adapted for rocking movement about two co-planar and perpendicular axes both passing through the axis of the spray discharge means, and driving means following an orbital path and connected to one end of the mounting means on one side of the plane of said co-planar axes whereby the discharge end of said spray discharge means on the other side of the plane of said co-planar axes is moved in a similar orbital path, and material discharged therefrom coats the interior of articles presented thereto.

5. In a machine of the class described, having means to convey articles to be coated and having spray discharge means directed toward the path

of said articles, the latter having interior surfaces facing in various directions, mounting means for said spray discharge means including a U-shaped yoke pivotally mounted on an axis passing through the base of the yoke and midway between its arms, a bracket connected at one end to the spray discharge means and pivotally mounted between the arms of said yoke on an axis perpendicular to and intersecting that on which the yoke is mounted, driving means following a fixed path connected to the other end of said bracket so that the bracket pivots with respect to said yoke and said yoke pivots about its mounting whereby the discharge end of said spray discharge means moves in a similar fixed path to discharge a spray at various angles and

directions to produce an even coating on the interior of said articles.

6. A machine for the class described having means for conveying articles to be coated, a plurality of spray discharge means tiltably mounted to direct sprays at various angles toward the path of said articles and driving means for moving the spray discharge means during the coating operation comprising two cranks, a connecting rod with each end connected to one of the cranks, and means separately spaced along the connecting rod between the cranks for contacting and transferring to each of the spray discharge means a component of the movement of the connecting rod.

HAROLD A. ROSELUND.
